UNITED STATES PATENT OFFICE.

WILLIAM H. MARZOLF, OF RACINE, WISCONSIN,

WEATHER-STRIP.

1,101,301.

Specification of Letters Patent. Patented June 23, 1914.

Application filed April 12, 1913. Serial No. 760,732.

To all whom it may concern:

Be it known that I, WILLIAM H. MARZOLF, a citizen of the United States, residing at Racine, in the county of Racine and State 5 of Wisconsin, have invented new and useful Improvements in Weather-Strips, of which the following is a specification.

This invention has relation to weather strips and it consists in the novel features 10 hereinafter described and claimed.

An object of the invention is to provide a strip of simple and cheap structure especially adapted to be used in conjunction with windows or doors arranged to swing 15 inwardly with relation to their frames. The parts are so arranged that when the window is closed, the members constituting the strip bridge the spaces between the edges of the window sash and the frame and prevent the 20 passage of air and moisture. These members are also so arranged as to direct the moisture away from the window sash so that it cannot accumulate and freeze and thereby interfere with the movement of the 25 sash. With these objects in view the weather strip includes members fixed to the side of the sash and adapted to overlap the edge portions of members loosely mounted upon the window frame. When the sash is open, 30 the members upon the frame may be moved in close proximity to the surfaces of the frame and therefore the presence of the said members upon the frame will not obstruct the window opening therein.

35 In the accompanying drawings—Figure 1 is a perspective view of a window sash and frame with the weather strip applied. Fig. 2 is a transverse sectional view of one form of the strip. Fig. 3 is a transverse sectional view of another form of strip.

The weather strip comprises strip members 1 which are secured in fixed position to the outer side of the sash in the vicinity of the edges thereof. The members 1 are 45 provided with angularly disposed edge portions 2 and 3. The edge portion 3 lies in close contact with the outer surface of the sash and securing screws 4 pass transversely through the portions 3 and secure the members to the sash. The portions 2 of the members 1 are disposed at acute angles to the 50 outer surface of the sash.

55 Strip members 5 are loosely secured by means of screws 6 to the sides of the window frame and may be swung into position parallel with the surfaces of the said sides

to positions at acute angles to said surfaces. When the sash is closed in the window frame, the portions 2 overlap the inner portions of the members 5. At the top and sides 60 of the frame, the portions 2 lie against the inner surfaces of the members 5 while at the sill or bottom of the frame, the portions 2 lie against the outer surfaces of the members 5. Clips 7 are secured to the outer side of the members 5 at the sill of the window frame and are adapted to lie over the outer surface of the portion 2 of the lowermost strip member 1. The end portions of the clips 7 project beyond the inner edge of 65 the strip member 5 at the sill of the frame and consequently when the sash is closed in the frame, the lower edge of the portions 2 of the lowermost strip member 1 may be readily passed between the outer surface of 70 the lowermost strip member 5 and the under surfaces of the clip members 7. Therefore when the sash is closed in the window frame, the overlapping strip members bridge the spaces between the edges of the sash and 75 the surfaces of the frame and consequently they will prevent the passage of air through the said spaces and will also shed water or moisture which is also prevented from passing through the said spaces. By reason of 80 the angular disposition of the strip members with relation to the sash and the frame when the sash is closed, the moisture is directed away from the sash and consequently it can- 85 not freeze and interfere with the movement 90 of the sash.

By reason of the fact that the strip members 5 are loosely connected with the sides and sill of the frame, the said members may be swung in close proximity to the said 95 sides and sill when the sash is in a position and therefore they present no obstruction through the opening of the frame. When the sash is in a closed position in the frame, the portions 2 of the strip members 1 hold 100 the inner portions of the strip members 5 away from the sides of the frame and when the clips 7 are over the upper surface of the portions 2 of the lowermost strip member 1, the inner part of the lowermost strip 105 member 5 is held up away from the sill and in close contact with the undersurface of the said portion 2.

Having described the invention what is 110 claimed is:

In combination with a frame and sash, plane strips loosely mounted upon the sill

and stiles of the frame, and strips having angularly disposed edge portions fixed to the lower and side portions of the sash, the strips being so arranged that when the sash is in a closed position in the frame the strips at the sides of the sash will overlap against the inner sides of the strips at the sides of the frame and the strip at the lower portion of the sash will overlap against the outer side of the strip upon the sill of the frame, and clips carried by the strip

on the sill of the frame and engageable with the strip at the lower portion of the sash to hold the last mentioned strips in close contact with each other.

In testimony whereof I affix my signature in presence of two witnesses.

WILLIAM H. MARZOLF.
